DUAL-INDICIA CONTAINER

Thomas E. Clagett, Saginaw, Mich.

Application March 24, 1952, Serial No. 278,280

5 Claims. (Cl. 41—22)

1

This invention relates to new and useful improvements in milk-drinking mugs. It provides for means in connection with the said drinking mug to induce children to consume the entire contents of the mug, in order that the may see an interesting, changing facial expression on the front transparent wall portion, such as for instance, a picture of a frowning or laughing clown's face, relatively centered to create the most desired effect.

At no time has a drinking mug provided for such pleasant changeable pictures that could stir the interest of children enough to coax complete consumption of the milk contained in the mug. My invention is so constructed that a child can be relied upon to drink the milk with little encouragement or coaxing from another person.

An object of the present invention is to provide a container having dual indicia or pictures thereon, wherein one of the indicia is emphasized when the container is full of fluid and the other indicia is emphasized when the container is empty.

Another object of the invention is to provide a container having different colored labels or pictures on the forward wall thereof, wherein one face is accentuated when the container is full and the other face is accentuated when the container is empty.

Another object of the present invention is to provide a colored plastic mug with a handle affixed thereto which can be easily used by a child, and an interesting changeable facial expression on the front wall which will stimulate a child that ordinarily does not like milk to consume the entire contents of the mug in order that the clown's face will smile and not frown.

A further object of the present invention is to produce a mug of the character described in which the maximum simplicity of construction is secured.

According to the present invention, a novel container is provided having a substantially translucent colored wall portion and opposed thereto a transparent wall portion bearing dual indicia responsive to the level of a substantially opaque fluid in said container.

For further comprehension of the invention, and of the objects and advantages thereof, reference is made to the following description and accompanying drawings, and to the appended claims in which the various novel features of the invention are more particularly set forth. The inventive idea is capable of receiving a variety of mechanical expressions, one of which, for the purpose of illustration, is shown in the accompanying drawings, in which—

2

Figure 1 is a front elevational view of a mug showing a frowning clown's face.

Figure 2 is a front elevational view of a mug showing a laughing clown's face.

Figure 3 is a front elevational view of a mug showing both a frowning clown's face and a laughing clown's face.

Figure 4 is a full cross section taken on the line IV—IV of Figure 3 and showing the translucent back wall of the drinking mug and the transparent front wall having the contrasting colored faces thereon.

Referring with more particularity to the drawings, Figure 1 shows a mug 10 having a frowning clown's face 11, or other indicia such as a label, drawing, or picture painted the same color as the substantially translucent rear wall portion 12. Figure 2 shows the mug having a smiling clown's face 13, or other indicia, painted white, the same color of milk 16, for example, or any color that approximates the color of the fluid to be used in the container. It is to be understood that various colors can be used for the frowning clown's face, but red has been selected for illustrative purposes because it renders the face more vivid and interesting to children. If chocolate milk, or some other like-colored fluid were used in the mug the smiling clown's face would be painted to contrast with the color of that fluid. For example, if orange juice were to be used in the mug, the smiling clown's face would be painted with an orange color.

When the mug contains milk, the white smiling clown's face will be rendered invisible against the white background and the milk will render invisible the substantially red translucent rear wall portion, thereby emphasizing the frowning clown's face. As the contents of the mug are being emptied, the red frowning clown's face will be gradually rendered invisible against the substantially red translucent rear wall portion and the white smiling clown's face will stand out and become increasingly visible. If milk is left at various levels in the mug, interesting, fascinating and changeable expressions will appear on the front wall portion 15 of the mug. When the contents of the mug are completely emptied, the white smiling clown's face will become the dominant expression.

Figure 3 shows a mug having both a frowning clown's face 11 and a smiling clown's face 13 on the front wall portion 15 thereof. The mug has a handle 14 affixed to the side thereof, but the handle can be placed in other positions relative to the mug or omitted entirely, if desired. For example, if the mug were constructed substan-

tially in the shape of a pail, the handle could be affixed to the top of the mug.

Summarizing, it will be seen that tumbler, mug, or glass is prepared in such a manner that if a plane were passed through the longitudinal axis of the container one side of the container so-divided is colored and opaque or translucent. The other side or wall is made transparent. Upon the transparent half of the container wall non-coinciding patterns or indicia in two contrasting colors are arranged as shown in Figure 3. It will be noted that Fig. 3 combines the indicia shown in Figs. 1 and 2 and that the arrangement is such that no portion of the indicia overlaps or is superimposed upon the other indicia. The indicia may be printed on the transparent wall or may be transferred thereto by means such as decalcomania. As shown in Fig. 3 all of the indicia are arranged upon the transparent portion of the container. One color is represented by the indicia appearing in Fig. 2 and the other color, corresponding to the colored opaque or translucent side of the glass is represented in Fig. 1. When the glass is filled with milk, for example, that portion of the mug having the painted indicia shown in Fig. 2 cannot readily be discerned because the color selected for that indicia is white and blends with the color of the milk so that milk and indicia of Fig. 2 become a solid white background. A contrasting indicia (say red for illustrative purposes) as represented in Fig. 1, predominates because it contrasts strikingly with the white background of the milk. As the milk is consumed the opaque or translucent red colored side of the glass becomes visible through the transparent side of the container and the formerly discernible red indicia or pattern blends with the red background of the glass so that the prominence of the red pattern is lost by blending with the now red background. Now, with the container empty, the contrasting white indicia is accentuated against a generally red background.

It will be understood that the fundamental principle of the invention may be carried out in diverse ways, but for the purpose of the instant disclosure and accompanying drawings a glass or plastic mug has been selected as the subject upon which the faces are produced. In other aspects the invention comprehends the employment not only of the various means described, but of equivalent means for performing the recited function. As might be presumed, the representation of the faces on the front wall portion is applied by coating, painting, impressing, etching, or otherwise. Moreover, the article upon which the faces are portrayed is not limited to a mug. It may be any other type of container, bottle or vessel. It may be a hollow cube with an opening for milk or some other fluid; or it may be made of some material similar to glass or plastic. The article may be triangular, rectangular or any other shape so as to comply with the basic features of the invention.

The substantially translucent colored wall portion of the container is preferably translucent so that when the mug is empty, light entering through the rear wall will help blend and perfect the like-colored face on the front wall. A somewhat more opaque rear wall portion is also operative in the present invention, but would not be as satisfactory as the substantially translucent rear wall portion. By dual indicia, I mean that any kind of markings can be positioned on the transparent forward wall, for example, labels,

drawings, pictures and the like. The substantially opaque fluid inside the container can be of various types. Fluids in a liquid state are preferred, but other fluids, such as dense gases and the like, will achieve similar effects.

Various modifications may be made in the device of the present invention without departing from the spirit or scope thereof and it is to be understood that I limit myself only as defined in the appended claims.

I claim:

1. A container having a substantially translucent colored wall portion, and opposed thereto a transparent wall portion bearing non-coinciding dual indicia, responsive to the level of a substantially opaque fluid in said container one of said dual indicia substantially the same color as said translucent wall portion, and the other of said indicia substantially the color of said opaque fluid.

2. A dual indicia drinking mug for substantially opaque fluids comprising: a substantially cylindrical container, the rear wall of said container being of colored translucent material and the front wall being of transparent material; two substantially opaque patterns upon said transparent wall of contrasting import, one of said patterns being substantially the color of said rear wall, the other of said patterns being substantially a color contrasting to the color of said rear wall and corresponding to the color of said opaque fluid.

3. A drinking mug for substantially opaque fluids, the rear wall of which is composed of a substantially translucent colored material and the forward wall being of transparent material, a frowning clown's face of the same color as the rear wall arranged and fixed upon said forward wall, and a laughing clown's face fixed on said transparent wall of the color corresponding to the color of the said opaque fluid to be used in said mug and of a contrasting color from said colored rear wall.

4. A handle attached drinking mug for substantially opaque fluids, the rear wall of which is composed of a substantially opaque colored material and the forward wall being of transparent material; a frowning clown's face of the same color as the rear wall arranged and fixed upon said forward wall, and a laughing clown's face arranged on said transparent wall in a color contrasting with that of the color comprising said frowning clown's face and corresponding in color to the said opaque fluid.

5. In a drinking mug for milk the combination including: a transparent wall on one side of said mug; a red colored wall opposite said transparent wall on the other side of said mug and visible through said transparent panel; two patterns upon said transparent wall, one of said patterns being red and the other of said patterns being white, the said red pattern being visible when said mug is filled with milk and the said white pattern being visible when said mug is empty.
